MOLDS FOR PLASTIC MATERIALS

James A. Sinclair, Franklin, La.

Application January 17, 1956, Serial No. 559,600

1 Claim. (Cl. 25—130)

This invention relates to molds designed primarily for use in the manufacture of concrete structures or receptacles such as septic tanks. More specifically, this invention concerns an improved concrete mold in which the casting can be quickly and easily released from the confining walls of the mold.

Generally speaking, casting methods and apparatus now available, whether particularly adapted for casting structures from materials such as concrete, or whether adapted for casting from plastic material, have not satisfactorily solved the problem of disengaging the hardened casting from the confining walls of the mold. In the past in order to separate a heavy casting from the inner core of a mold it has been necessary to laboriously turn the entire mold.

It is thus the principal object of the present invention to provide a mold which effects the expeditious release of the casting from the confining structure without employment of the time consuming and laborious methods which have been used in the past.

A further object of the present invention is to provide a novel and advantageous relation of the outer and inner mold wall allowing the outer wall to be removed without disturbing the inner wall.

A still further object of the present invention is to provide a novel and advantageous relation of the outer wall and casting supporting member permitting the removal of the outer wall and release of the casting through movement of the supporting member.

Another object of the present invention is to provide a mold of simple, strong, durable and inexpensive construction.

Other objects, features, and advantages will be apparent from the following description read in conjunction with the accompanying drawings in which certain embodiments of the invention are illustrated by way of examples.

In the drawings,

Figure 1 is a plan view of a mold embodying the principles of the invention;

Figure 2 is a horizontal cross section taken along the lines 2—2 of Figure 1;

Figure 3 is a fragmentary view, on an enlarged scale, showing the threaded pressure elements disposed about the angle iron shown in Figure 1;

Figure 4 is a fragmentary perspective view of the flanged angle iron shown in Figure 3; and

Figure 5 is a view similar to Figure 3 but a modification permitting the use of the same basic mold and supporting structure for casting receptacles of varying depths.

Referring now to the drawings in more detail, there is shown at 10 a frusto-conical core or inner form about which the concrete is poured. This shape has been found most useful in the manufacture of septic tanks. However, it will be readily apparent that the shape and size of core 10 may vary considerably. At 11 there is shown a confining wall surrounding and spaced from core 10 when in assembled position. Wall 11 may, if

2

desired, consist of a split jacket having two or more sections which fit about core 10 and are appropriately attached at their adjacent edges. The area immediately above core 10 remains uncovered so that concrete may be poured between core or inner form 10 and wall 11 to any desired level. The concrete disposed above core 10 then becomes the top or bottom of the tank section thus formed. Guiding members or bushings are shown at 13 which fit about aperture 14 in wall 11. Though two of these spout-like guiding members or projections and associated apertures are shown, it will be evident that more than two may be provided, if desired. Pins 15 are inserted through the members 13 and apertures 14 to abut inner core 10 when concrete is poured into the form. In this way, holes are formed in the casting into which suitable grapples may be inserted to lift the casting from the mold.

The inner core 10 rests on and is welded or otherwise secured to suitable supporting members such as the channel irons generally indicated at 16 and 17. It will be readily appreciated from Figure 2 that these channel irons are crossed and project beyond the area of core 10 to provide support for annular angle iron 18.

The angle iron ring or annulus 18 is disposed about and embraces the inner core 10. As may be seen most clearly in Figures 3, 4 and 5, the vertical portion 19 of the ring 18 fits about the core 10 while the horizontal portion 20 supports the casting 21 and at the same time provides support for the outer wall 11. The ring 18 may additionally be provided with a plurality of horizontal flanges 22. Four horizontal flanges 22 have been found preferable though it will be evident that the number may vary considerably without departing from the spirit of the invention. In the drawings, angle iron 18 is shown as a ring, but the shape of angle iron 18 may vary considerably, depending upon the contour of the tank or receptacle desired, the only limitation being that it snugly fit about core 10 and not be fixedly secured thereto. However, it is most important that angle iron 18 be capable of vertical displacement along core 10.

Fixedly secured to outer wall 11 are a plurality of outwardly projecting bracket members 23, these bracket members being provided with horizontal flanges having threaded apertures for the reception of set screws 25. Four brackets and associated set screws have been found preferable, though the invention is not limited to this number. The set screws 25 threaded through the apertures in bracket members 23 abut the horizontal flange 22 of angle iron 18. Thus, by tightening set screws 25 in the apertures of bracket members 23 and nuts 24, the outer wall 11 of the mold to which these screws are operatively secured is forced upward, thus releasing casting 21 from wall 11. In this way a very effective means for forcing the outer wall 11 upward is provided. It will be readily appreciated, however, that the present invention in its broadest aspects contemplates the employment of other lifting means as well as the threaded pressure elements described.

Channel bars 16 and 17 are provided with a plurality of threaded apertures 26 which accommodate associated set screws 28. By screwing set screws 28 through apertures 26 against angle iron 18 the casting is loosened from its position against inner core 10 and may then be easily removed from the core. Lock nuts 29 may be provided on the screws or bolts 28 if desired. Hydraulic pressure or other lifting means may be used, if desired, in lieu of threaded pressure elements though the set screw assembly described is preferred.

In operation, the present invention is keyed to ease and facility of operation. Inner core or form 10 is welded or otherwise attached to the cross channel bars 16 and 17. The angle iron ring 18 is then placed about

the inner core 10 so that its vertical portion 19 abuts core 10 and its horizontal portion 20 lies substantially parallel to the channel bar upon which it rests. Angle iron 18 thus serves as a floor for the mold and as a supporting member for the outer wall 11. The set screws 28 are placed in their lowermost position and may be turned in their apertures 26, until they barely abut the under side of the angle iron 18. The outer wall 11 is then placed about the inner core, leaving space as is shown most clearly in Figure 1 for the reception of concrete or other suitable plastic material. This outer wall 11 may be secured in place by any suitable means. Thus, the outer wall 11 may be secured in place by pins and clamps. For example the base of the outer wall 11 may be provided with an outwardly extending horizontal angle. Corresponding holes may then be drilled through this angle and horizontal flange 22 of angle iron 18 about the diameter of the form and tapered pins inserted to maintain the form in its proper position. The set screws 25 and associated nuts 24 are then positioned in bracket 23 as shown. At this time, if desired, core pins such as 15 may be inserted in the apertures 14. The casting material is now poured into the recess between the inner core 10 and the outer wall 11, over the top of the form, struck off level, and allowed to harden. Before complete hardening, pins 15 may be removed. Set screws 25 are then turned so that outer wall 11 is urged upward and loosened from its position surrounding casting 21. The wall 11 may then be lifted off. The set screws 28 may then be similarly turned to urge rolled angle iron 18 upward, thus loosening the casting so that it may be easily removed from the mold. It has been found that tightening set screws 28 as little as $\frac{1}{16}$ " is sufficient to release the casting from the core 10 even when bearing the weight of the outer wall of the mold. It is thus possible to completely free the casting 21 from the inner core 10 and outer wall 11 with a minimum of effort. The hardened casting may then be lifted through the use of the lift holes formed by pins 15.

When desired, a second angle ring 35 may be disposed at any point along the height of the inner core 10, depending on the size of the tank required. Thus, when a smaller ring 35 is called for, a series of legs or elevating members 31 may be employed to hold the angle iron 35 at any height along core 10. This elevating member may be placed upon angle iron 18 as shown in Figure 5. It will be immediately evident that outside form 11 rests on angle iron 18 even when a second angle iron 35 is employed. In this way it is possible to construct a casting which is smaller than the inner mold without the employment of a different core and outer wall assembly. This aspect of the invention has found particular value in the manufacture of septic tanks of different sizes. By positioning a rolled angle iron ring 35 at different levels about inner core 10, septic tank cores of different dimensions and capacity may be constructed with relatively little additional expense since only an additional angle iron of proper diameter is necessary. The present invention has, as a consequence, the great advantage of being both economical and easily adapted to the manufacture of a great variety of concrete products of different shapes and sizes.

The above described method of making variable sized shell-like receptacles or receptacle parts fits in very well with the manufacture of septic tanks of variable capacities. Boards of Health in certain municipalities sometimes have regulations requiring larger septic tanks in some cases than in others and this method of manufacture provides flexibility in meeting these demands, while using much of the same basic form and supporting frame materials. For example, two tub-like frusto-

conical castings such as shown in Figure 1 of the drawings, can be cemented together face-to-face, and with a maximum size half-receptacle the combined tank might have a capacity of 750 gallons to meet demands for a large size tank. For an approximate minimum requirement of 500 gallons, two smaller size half-tanks could be made according to the illustration in Figure 5 of the drawings; and if an intermediate size tank of, say, 600 gallons were required, one large size half-receptacle and one smaller size half-receptacle could be united to form the finished tank. Of course, pipe inlet openings for the tanks can be provided by making suitable perforations in the walls 10 or 11 and inserting the necessary core forms.

It will, of course, be readily understood that, although the present invention has been described in great particularity with reference to the preferred embodiment shown in the accompanying drawings, the specific structure shown and described may be modified considerably without departing from the spirit of the invention.

Having thus described this invention, what is claimed as new and desired to be secured by Letters Patent is:

Mold apparatus for a hollow concrete casting such as an open-ended receptacle or the like, said apparatus comprising a supporting frame; a centrally disposed core member rigid with said supporting frame, the outer casting-contacting surface of said core member being substantially frusto-conical in configuration; an annular vertically displaceable bottom plate surrounding said core member and disposed in contact with the lower outer margins of said core member when the bottom plate is located at its lowermost operable position for casting; an outer mold wall member surrounding and spaced radially outwardly from said core member a distance equal to the wall thickness of the hollow casting desired, the lower edges of said outer wall member resting upon said bottom plate when the mold parts are in operative casting position; said bottom plate comprising an annulus of angle cross section having an outwardly extending horizontal flange upon which the casting and the outer mold wall member rest, and a radially inwardly disposed depending vertical flange which, in its lowermost position for casting, rests upon said supporting frame; first screw-jack means threaded through a portion of said supporting frame and disposed to contact the bottom surface of said bottom plate, exert upward pressure thereon, and thus force the casting-supporting bottom plate and the core member apart vertically, the tapered configuration of the core and casting serving to accomplish the effective separation of those parts through a relatively short movement of said first screw-jack means; radially outwardly projecting brackets secured to the lower portions of said outer wall member; second screw-jack means threaded through said brackets; radially outwardly projecting ledges formed on said bottom plate; said second screw-jack means disposed to contact upper portions of said ledges, exert a downward pressure thereon, and thus force said casting-supporting bottom plate and the outer wall member apart vertically; the tapered configuration of the wall member and casting serving to effect the prompt separation of the parts through a relatively short movement of the second screw-jack means, all whereby the hollow casting may be readily dislodged from the mold apparatus.
